Fig. 1.

This technical drawing illustrates a mechanical assembly, likely a component of a larger machine. The vertical section on the left features a piston 12 connected to a rod 13. The rod 13 is guided by a curved track 14, which is supported by a base 11. The horizontal section on the right consists of a cylinder 15 connected to a rod 16. The rod 16 is connected to a lever 17. A vertical rod 18 is attached to the cylinder 15. A lever 19 is connected to the vertical rod 18. A horizontal rod 20 is attached to the lever 19. A lever 21 is connected to the horizontal rod 20. A vertical rod 22 is attached to the lever 21. A spring 23 is attached to the vertical rod 22. A vertical rod 24 is attached to the cylinder 15. A lever 25 is connected to the vertical rod 24. A vertical rod 26 is attached to the cylinder 15. A lever 27 is connected to the vertical rod 26. A vertical rod 28 is attached to the cylinder 15. A lever 29 is connected to the vertical rod 28. A vertical rod 30 is attached to the cylinder 15. A lever 31 is connected to the vertical rod 30. A vertical rod 32 is attached to the cylinder 15. A lever 33 is connected to the vertical rod 32.

BALL LOADING MACHINE

Frank B. Kalister, Cleveland, James O. Stafford, Painesville, and Frank J. Konyvka, Maple Heights, Ohio, assignors, by mesne assignments, to Jack & Heintz Precision Industries, Inc., Cleveland, Ohio, a corporation of Delaware

Application April 30, 1945, Serial No. 591,132

5 Claims. (Cl. 29—201)

1

This invention relates to a novel machine for inserting balls in ball bearing races. The object of the invention, in general, is to produce a hopper fed machine for automatically inserting a proper number of balls in the races of ball bearing assemblies with a minimum of handling and attention required by an operator to achieve greater speed in production than is possible by hand assembly, and to facilitate cleanliness by keeping the highly polished balls in a closed hopper until they are assembled with their associated bearing races.

Other objects and advantages become apparent as the specification proceeds in connection with a preferred embodiment illustrated in the accompanying drawings in which:

Figure 1 is a sectional view through the machine of the present invention taken approximately on the line 1, 1 of Figure 2;

Figure 2 is a plan view of the machine;

Figure 3 is a sectional view through the ball hopper;

Figure 4 is a sectional view approximately at right angles to Figure 1, taken on the line 4, 4 of Figure 2, and showing the parts in a different position than Figure 1;

Figure 5 is a sectional view taken approximately along lines 5, 5 of Figure 2; and

Figure 6 is a top plan view of the vertical ram.

The parts of the present machine extend above and below a table or bench top 1, carrying a shelf 2, provided with an incline slide 3 for feeding ball races by gravity. The slide 3 is preferably covered by a transparent panel 4 to exclude dust from the ball races as they are fed into the machine. Supported upon the table 1 is a ball hopper 5, having a cover 6, carrying a hand operated agitator or stirring element 7. The bottom of the hopper is provided with a number of openings 8 equal to the number of balls to be inserted in each bearing assembly, and transparent tubes 9 are provided in the manner shown to carry the balls down to a loading chamber 10.

The loading chamber 10 comprises a vertical cylindrical bore in a supporting block 11 beneath the ball hopper, a piston 12 is slidably received within the bore and loading chamber 10 so as to occupy a lower position as shown in Figure 1 to normally retain the balls in the tubes 9 and prevent their admission into the loading chamber until the proper time. The piston 12 carries an agitating rod 13 extending inwardly into the bottom of the ball hopper 5, the piston and agi-

2

tator being urged to their lowermost position by a spring 14. A groove 15 in one side of the piston receives the end of a set screw 16 to prevent rotation of the piston and to provide limits for its motion in reciprocation.

The loading chamber 10 is provided with rounded corners 17 at its lower end and terminates at a distance above the table slightly greater than the thickness of the ball races to be loaded. Directly beneath the loading chamber 10 is a circular opening 18 in the table 1, receiving a vertical ram 19 having a disc-like cam follower 20 adapted to be constantly rotated and intermittently raised and lowered by a cam 21 on a power driven shaft 22. The upper end of the ram 19 is provided with a hemispherical ball center 23 and a plurality of sharp radial projections 24 for purposes to be presently described. A spring 25 resiliently urges the ram 19 into constant driving engagement with the cam 21. A gear 26, on the shaft 22, drives a gear 27 which in turn meshes with a gear 28 carrying a finger 29 positioned to impart a step-by-step movement to a star wheel 30. The purpose of the star wheel 30 is to drive the intermittent feed disc 31 which receives ball races from the lower end of the slide 3 and transfers them one at a time into position between the ram 19 and the loading chamber 10. A curved guide rail 32 cooperates with the intermittent feed disc 31 in obtaining the proper alignment of the ball races as they arrive under the loading chamber 10. In order to prevent any coasting action of disc 31 and to assist the latter in the proper positioning of the ball race a leaf spring 44 is secured at 45 to overlap the disc and provide a predetermined resilient braking action on the latter. For convenience in cleaning or removing a jammed part, a clamp 46 is provided to hold the ball loader, as a unit, secure. Dowel pins 47 and 48 are used to hold the ball loader as a unit in direct alignment with feed disc 31. This provides a quick and easy means for repair and maintenance of the machine.

45 The above described mechanism is driven by an electric motor 33 to a reduction gearing 34 and an overload release clutch 35 so that if any part of the feeding mechanism should jam, the clutch 35 would over-ride to prevent damage to the parts.

The present embodiment of the invention is designed for loading six balls into an annular cage 40 associated with an outer race 41 of the type shown. In the present instance the cage 40 is made of non-metallic material having ball apertures 42 in the form of sockets having an inside

opening smaller than the ball diameter so as to prevent passage of the ball into the interior of the cage. The balls are introduced into the loading chamber in registry in positions corresponding to the spacing of the ball apertures 42 by means of bores or tubes 43 which receive balls from the tubes 9. Thus, if there are six balls in the bearing assembly they would be spaced 60° apart in the cage 40 and so the bores 43 are inclined slightly downwardly and spaced radially at 60° intervals around the loading chamber. Since the cages 40 are not indexed in rotation as they are raised into the loading chamber the ball apertures 42 did not necessarily register with the bores 43 without some amount of rotation. For this purpose the cam 21 is provided with a high portion having an annular extension sufficient to impart rotation to the cage 40, at least equal to the angular spacing of the ball apertures. This annular rotation may exceed the spacing of the balls and may be arranged to provide passage of each ball aperture into registry with at least two successive bores 43 if desired.

As previously stated, two of the primary objects of the present machine are to achieve a rapid assembly for production line operation with little manual attention, and the exclusion of dust and foreign particles which would render the bearing assemblies unsuitable for delicate precision instruments. The present machine accomplishes these primary objects by providing a feeding and loading mechanism capable of rather rapid operation and by obviating handling of the parts and prolonged exposure to atmospheric dust and other sources of contamination.

In operating the machine an operator has merely to load the ball-hopper 5 from time to time which does not involve contact of the highly polished balls with the skin or perspiration of the operator, and the feeding of the races from the shelf 2 into the slide 3, which may also be accomplished without requiring actual contact with the operator's hands. In their passage down the slide, the assemblies are protected from dust by the transparent cover 4 and an additional transparent cover may be provided over the short feed path associated with the feeding disc 31 so as to practically exclude the possibility of contamination throughout the whole feeding and loading operation.

In feeding the machine, the cages 40, having an external diameter slightly less than the smallest opening in the external race, are placed within the race, as shown in Figures 1 and 2, and the parts are delivered in this relationship to a rest position immediately over the ram 19 and beneath the loading chamber 10. The cam 21 is timed with respect to the feed disc 31 so that when an assembly has been placed in position as shown in Figure 1, the ram 19 will begin to elevate with a rotary motion to carry the cage up into the loading chamber with ball apertures 42 on a level with the loading bores 43. The rounded corners 17 facilitate entry of the cages into the loading chamber, the centering action being associated by the twist imparted to the cage by a plurality of sharp projections 24 on the upper end of the revolving ram 19. Any slight misalignment of the assembly between feed disc 31 is corrected by the ball projection 23 which automatically centers the whole assembly upon engagement with the cage in the position shown in Figure 1 so that the ram 19 will pass freely through the middle of the race 41. If the ball apertures 42 are not in registry with the loading bores 43

when the cage arrives in loading position they will be rotated past one or more of the ball loading bores 43 before the cage descends so as to insure certain loading of all the apertures. As the ram 19 descends, the loaded cage follows it into the race and then the loaded assembly is ejected by the movement of the next assembly into position over the loading ram.

In the various views the balls have been omitted in certain instances to more clearly show the operation of the mechanism in the various positions of its parts, it being understood that the slide 3 is to be constantly filled with assemblies as shown in Figure 2 and that the hopper 5 is to be kept supplied with balls, during the operation of the machine.

The present machine may obviously be adapted to various assemblies of different types and having a different number or so of balls, it being understood that the present preferred embodiment is shown and described merely for the purpose of illustrating the purpose of the invention. All changes and modifications falling within the scope of the appended claims are included in the invention.

We claim:

1. A ball loading machine comprising a ball loading chamber, a hopper feed for supplying balls to said chamber in radial directions there-around, means for feeding ball cage and bearing race sub-assemblies one at a time to a station adjacent said loading chamber, and means for moving said cages out of said bearing races into said loading chamber with a longitudinal and rotary motion so as to bring said cages into proper registry with said ball feeding means.

2. A ball loading machine comprising a ball loading chamber, a plurality of ball feeding means entering said chamber radially at angles corresponding to the ball positions in the ball cage to be loaded, means for feeding cage and bearing race assemblies by intermittent motion to a station adjacent said loading chamber, and means geared to said feeding means for moving a cage out of its associated bearing race and into said loading chamber with a longitudinal and rotary motion and subsequently replacing said cage when loaded within said bearing race in assembled relation therewith.

3. A ball loading machine comprising a loading chamber, a plurality of ball feeding tubes entering said chamber radially at angles corresponding to the arrangement of balls in the cage to be loaded, gravity feed means for delivering cage and bearing race sub-assemblies one at a time on a supporting surface, intermittent feed mechanism for feeding said sub-assemblies to a station adjacent said loading chamber, and intermittently reciprocating means for moving a cage out of its associated bearing race and into said loading chamber in alignment with said ball feeding means with a longitudinal and rotary motion, and to return said cage when loaded to said bearing race in assembled relation therewith, and over-riding clutch means for disconnecting a source of power in the event of jamming of any part of the mechanism.

4. A ball loading machine comprising a vertical cylindrical ball loading chamber, a plurality of ball feeding tubes entering said chamber radially, means to feed cage and bearing race assemblies to a station in alignment beneath said chamber, a vertical ram beneath said station in alignment with said chamber, and means to raise and rotate said ram to cause said ram to pass through

said bearing race carrying said cage into said loading chamber with a rotary motion to cause ball apertures therein to register with said ball feeding means and to thereupon return to starting position to assemble the loaded cage within said bearing race.

5. A ball loading machine comprising a vertical cylindrical loading chamber, a plurality of ball feeding tubes entering said chamber in radial directions therearound, a piston within said chamber adapted to cover the ends of said ball feeding tubes to prevent the admission of balls into

said chamber, intermittent feeding mechanism for depositing bearing cage and race assemblies at a station vertically beneath said loading chambers, a vertical ram beneath said station and aligned with said chamber, and means to raise and rotate said ram in intermittent motion to cause said ram to pass through said race to elevate said cage and said piston and to rotate said cage as it is brought into ball loading position.
